UNITED STATES PATENT OFFICE.

JAMES H. KOON, OF ONARGA, ILLINOIS.

STOCK CAR.

Application filed January 8, 1921. Serial No. 435,893.

To all whom it may concern:

Be it known that I, JAMES H. KOON, a citizen of the United States, residing at Onarga, in the county of Iroquois and State 5 of Illinois, have invented a new and useful Stock Car, of which the following is a specification.

This invention relates to stock cars, and more particularly to the interior construction thereof, it being the primary object of 10 the invention to provide movable partitioning gates within the car, whereby the car may be divided into a plurality of compartments.

15 A further object of the invention is to provide gates of this character which may be readily folded to positions adjacent to the walls of the car, whereby the same may be out of the way, when the car is to be used 20 for shipping stores.

A still further object of the invention is the provision of means for supporting the 25 gates, whereby the same may be moved to positions to adapt the car for shipping stock of various sizes, such as hogs or cattle.

With the foregoing and other objects in view which will appear as the description proceeds, the invention resides in the combination and arrangement of parts and in the 30 details of construction hereinafter described and claimed, it being understood that changes in the precise embodiment of the invention herein disclosed, may be made within the scope of what is claimed, without departing from the spirit of the invention.

Referring to the drawings:—

Figure 1 is a vertical sectional view 40 through a stock car constructed in accordance with the present invention.

Figure 2 is a plan view thereof, the roof of the car being removed.

Figure 3 is a transverse sectional view 45 through the car.

Figure 4 is a fragmental detail view of a gate and its supporting means.

Referring to the drawings in detail, the car is of the usual construction including the supporting beams 5, and flooring 6 to

which are connected the standards 7 that 50 support the roof 8.

The side walls of the car are formed by the spaced longitudinal bars 9, the end walls thereof being formed by the spaced longitudinal bars 10, the spaces between the bars 55 permitting a free passage of air through the car to insure efficient ventilation of the car.

The supports for the partitions include a pair of relatively long rods 11, which have their ends bent at angles to permit the same 60 to be secured to the standard 7. The partitions or movable gates are formed preferably of frames 12 and the vertical and horizontal wires 13 and 14 respectively, there being provided link members 15 formed on one 65 edge of the respective gates to accommodate the rods 11 so that the gates or partitioning members may be moved longitudinally of the car to divide the interior thereof into stalls or compartments of various sizes. 70

Disposed along the opposite side of the car, are a plurality of keepers indicated at 16, which keepers are disposed in spaced relation with each other and accommodate the hook members 17, whereby the gates or partitions may be held in various positions of 75 adjustment.

A plurality of vertically adjustable gates are also supported in the car, and these gates are constructed similar to the gates previously described, except that the eyes 18 are disposed in horizontal planes and operate on the vertical rods 19, which rods have the upper ends thereof extending to points adjacent to the roof of the car. 80

Hook members 20 are carried by the opposite end of each partition, and as shown these hook members extend downwardly to permit the same to be passed through the keepers 21, whereby the gate may be held in 90 predetermined positions.

From the foregoing it is obvious that if the car is to be used for shipping hogs or the like, the gates may be moved to positions as shown by Figure 4 of the drawings, or to 95 positions where the lower edges of the gates are in close proximity with the floor of the car, but should the car be used for shipping

cattle such as horses, cows or the like, the gate may be moved upwardly, the lower hook member 20 being positioned in the upper keeper 21.

5 What is claimed is:—

In a stock car, supporting rods secured to one wall of the car, gate members having loops formed at one end thereof and adapted to embrace portions of the supporting rods, hook members at the opposite end of the gate members, keepers secured to the op-

posite wall of the car, said keepers adapted to receive the hook members of the gates, to secure the gates in various positions of adjustment.

In testimony that I claim the foregoing as my own, I have hereto affixed my signature in the presence of two witnesses.

JAMES H. KOON.
